UNITED STATES PATENT OFFICE.

THOMAS J. STURTEVANT, OF WELLESLEY, MASSACHUSETTS, ASSIGNOR TO STURTEVANT MILL COMPANY, OF BOSTON, MASSACHUSETTS, A CORPORATION OF MASSACHUSETTS.

AIR SEPARATOR.

Application filed January 5, 1926. Serial No. 79,376.

The invention to be hereinafter described relates to air separators for grading materials, wherein the separation is accomplished by an air current moving upward in a separating chamber and downward in a settling chamber. The air current is induced by a fan and is caused to circulate through the chambers, and inlet and outlet openings between them. The materials to be graded are fed into the separating chamber and are received by a rotary distributor which throws the materials out across the rising air current. The heavier particles whirl and gravitate down through the air current in the separating chamber and are delivered therefrom through a discharge spout, while the lighter particles are carried upward by the air current, pass through the outlet opening, and then gravitate downward in the settling chamber and are delivered therefrom through a discharge spout.

It is desirable to regulate the velocity of the air current, in order that the separator may be adapted for grading materials of different character. One of the purposes of the present invention, therefore, is to provide desirable means for varying the volume of the air current passing through the outlet opening. To accomplish this, in the present instance a rotary baffle plate is provided having means for adjusting the same toward or away from the outlet opening of the separating chamber, the construction being such that the nearer the baffle plate is to said opening, the greater will be the reduction in the volume of the air current passing upward through the opening.

Another purpose of the invention is to provide a simple and efficient adjustable valve for varying the size of the outlet opening. Another purpose of the invention is to provide distributor and baffle plates made of sections detachably secured together so that new plates may be readily substituted for worn ones. And still another purpose of the invention is to provide simple and efficient means for supporting the casing of the separating chamber on the outer casing of the separator, the construction being such that the inner casing may be levelled and its elevation varied in respect to the outer casing and the fan as required.

The character of the invention may be best understood by reference to the follow-

ing description of one good form of the invention shown in the accompanying drawings, wherein:

Fig. 1 is a vertical section through an air separator embodying the invention;

Fig. 2 on an enlarged scale is a view of a portion of the outer and inner casings illustrating the means for adjustably supporting the inner casing on the outer casing;

Fig. 3 is a horizontal section taken on line 3—3 of Fig. 1;

Fig. 4 on an enlarged scale is a vertical section through a portion of the rotary distributor;

Fig. 5 is a horizontal section taken on line 5—5 of Fig. 4;

Fig. 6 is a horizontal section taken on line 6—6 of Fig. 1;

Fig. 7 is a horizontal section taken on line 7—7 of Fig. 1; and

Fig. 8 is a sectional detail of bearings for the distributor carrying shaft.

Referring to the drawings, the air separator shown therein as one good form of the invention, comprises an outer casing 1 (Fig. 1) consisting of a drum 3 having a cover 5 and a cone 7 projecting down from the drum. Within and spaced from the outer casing is an inner casing 9 consisting of a drum 11 having a ring 13 at the top thereof leaving a central outlet opening 15. Projecting down from the drum 11 is a frusto-conical portion 17 and beneath the latter is a cone 19 provided with a tailings discharge spout 21 entered laterally through the lower portion 23 of the cone 7 of the outer casing. Said cone portion 23 having a fines discharge outlet 25 at the bottom thereof. In order that the tailings discharge spout 21 may face in four different directions, the cone portion 23 is formed separate from the cone 7 and the spout 21 has an upwardly flaring mouth 27 overlapping the lower end of the cone 19, and said mouth is connected by hanger bolts 29 with stiffening angle bars 31 on the cone 19. The construction is such that on release of the nuts of the hanger bolts 29, the cone portion 23 and the spout 21 may be given a rotative adjustment to cause the spout 21 to face in the direction desired, and then the nuts may be applied to the hanger bolts, thereby to secure the mouth 27 to the cone 19.

The inner casing is mounted on and sup-

ported by the cone 7 of the outer casing, and to accomplish this, legs 33 are provided, in the present instance, four in number. Each of said legs has its lower end swivelled in a split socket 35 secured to the cone 7 and provided with a clamp screw 36. The upper end is threaded to a cap 37 pivotally connected to one of the angle bars 31 of the cone 19. Threaded on the leg adjacent the cap 37 is a lock nut 39. The construction is such that on release of the clamp screws 36 and the lock nuts 39 the legs 33 may be given a rotative adjustment, thereby to raise or lower the cone 31 and properly level the same. Then the clamp screws 36 and the nuts 39 may be set up to secure the legs in the positions to which they have been adjusted. The frusto-conical portion 17 and the cone 19 of the inner casing are spaced to provide an inlet opening 41, and at this opening are vertical vanes 43 (Figs. 1 and 3) having their lower ends resting on and pivotally connected to a ring 45 secured to the upper end of the cone 19. A flange 47 projects outward from the frusto-conical portion 17 of the inner casing and rests upon and is pivotally connected to the upper ends of the vanes. The construction is such that the inner casing drum 11 and frusto-conical portion 17 are supported upon the vanes. These vanes may be individually adjusted to different angular positions to vary the velocity of the air current passing through the inlet opening 41, and the friction between the ends of the vanes and the ring 45 and the flange 47 will be sufficient to hold the vanes in the positions to which they are adjusted.

The space within the inner casing drum 11 and frusto-conical portion 17 constitutes a separating chamber 49, and the annular space between the inner and outer casings constitutes a receiving or settling chamber 51. To introduce the materials to be graded into the separating chamber, a feed spout 53 (Fig. 1) is provided on the cover 5, and communicates with a chute 55 projecting down through the outlet opening 15 referred to, and having a neck 57 projecting down a substantial distance into the separating chamber. The feed spout 53 is provided with a flap valve 59 pivotally mounted on the spout and having an arm 61 carrying a weight 63, the construction being such that flow of materials through the spout will hold the valve open, and when the flow of materials through the spout ceases, the weight 63 will close the valve and thereby prevent out-draft of the air through the feed spout. The materials passing down through the chute 55 are delivered to a rotary distributor, in the present instance, comprising a base 65 (Figs. 1, 4 and 7), and a lower circular plate 67 formed of sections 69 having

ing flanges 70 bolted together. The inner margins of these sections overlap the base 65 and are secured thereto. The construction is such that when the plates become worn they may be detached from the base and separated to facilitate their removal from the separator and the substitution of new plates therefor.

The base is secured to the lower end of a vertical shaft 71 which projects up through the chute 55 through a hole in the outer casing cover 5, and extends a substantial distance above the cover. This shaft is journaled in an upper bearing 73 carried by a gear housing 75 and is journaled in a lower bearing 77 beneath and secured to the cover. Fast on the shaft 71 is a collar 79 resting upon an end thrust ball bearing 81. Mounted on the top of the gear housing 75 is a lubricant cup 83 adapted to supply lubricant to the aforesaid bearings.

To rotate the shaft, a gear 85 is secured thereon directly above the ball bearing 81 in the gear housing, and meshes with a pinion 87 fast on a countershaft 89 journaled in bearings 91 and 93 mounted on the cover, the outer end of the shaft being provided with a pulley 95 which may be driven from any suitable source of power.

To stir the materials passing down through the feed chute 55 to the rotary distributor plate 67, vertical blades 97 are provided which may be entered up through slots in the base 65 and be detachably secured thereto by bolts. When the blades become worn they may be removed down through the base.

Located above the outlet opening 15 of the inner casing is a fan 99 comprising blades 101 secured to inclined arms 103 mounted on and secured to an upper flange of a hub 105 encircling the feed chute neck 57. This hub has a lower flange resting upon and secured to an internal flange 107 of a shell 109 encircling and substantially larger in diameter than the feed chute neck 57. At the lower end of the shell is an internal flange 111 which rests upon and is secured to the distributor base 65. To strengthen the shell it is provided with a series of upstanding internal ribs 113 extending between the internal flanges 107 and 111. The lower edge of the wall of the shell is a substantial space above the base, in order that the materials may flow out over the base between the ribs 113 onto the distributor plate 67.

When the vertical shaft is rotated, the distributor plate will be rotated, and since the shell and the fan are carried by the distributor base, the fan also will be rotated and will cause air to circulate up through the separating chamber through the outlet opening 15 and thence downward through the receiving or settling chamber and thence

through the inlet opening back into the separating chamber. The fan gives the air current a whirling motion in the settling chamber, and the whirling motion of the air in both the separating and settling chambers is promoted by the vanes 43.

The rotary distributor is provided with an upper or baffle plate 113 formed of sections 115 having upstanding flanges 117 bolted together. Said sections have inner marginal portions bolted to an angle ring 119 encircling the shell 109.

An important feature of the invention is the provision for adjustment of the baffle plate toward and from the outlet opening 15, thereby to regulate the air current passing through said opening. To accomplish this, in the present instance, three upright screws 121 are provided threaded in square nuts 123 seated in recesses in lugs 125 integral with the angle ring 119. The lower portions of these screws extend through bores in lugs 127 projecting outward from the shell 109; and in spaces between the lugs 127 and the distributor base are collars 129 fast on the screws and confine the same against longitudinal movement. The lower ends 131 of the screws may be squared to receive a suitable tool for imparting rotation to the screws. Holes 133 in the baffle plate 113 allow the screws to project therethrough, and the nuts 125 are confined in their recesses by marginal portions of the plate surrounding the holes 133. A vertical key 134 (Figs. 4 and 5) is set into a shallow groove 134^a in the shell and secured by screws to the shell. This key fits into a keyway in the ring and prevents rotative movement of the ring about the shell and thus relieves the screws 121 from this duty.

The construction is such that the screws may be rotated and operate through the nuts and lugs to move the baffle plate 113 up or down along the shell 109 to different positions of adjustment, and the screws will serve to hold the baffle plate in its different positions of adjustment. In Figs. 1 and 4, the baffle plate is in its highest position of adjustment. It may be lowered down substantially to the lower edge of the wall of the shell.

It may be desirable to vary the effective opening at the outlet 15 of the separating chamber for different classes of work. To accomplish this, a valve is provided comprising a series of lower plates or sections 135 (Fig. 6) resting upon the top ring 13 of the inner casing, said plates being of general oblong shape and in spaced relation to one another. Superposed upon the lower plates are upper plates or sections 137 of general oblong shape and disposed to cover the spaces between the lower plates. Each of the plates has a rod 139 secured thereto projecting radially outward through a guide

141 on the inner casing and a guide 143 on the outer casing, said rods being accessible externally of the outer casing for radial adjustment. To vary the effective opening of the valve, the rods are adjusted equally inward or outward, thereby moving the plates inward or outward relatively to the edge of the outlet opening in the top ring 13. The inner edges of the upper and lower plates collectively form an opening substantially circular in form, the adjustment of the plates serving to vary the diameter of the opening.

In operation, materials to be graded are introduced to the feed spout 53 and flow downward through the chute 55 to the rotary distributor plate 67. The materials flow outward in a thin stream over the distributor plate toward the wall of the inner casing drum 11 under the influence of centrifugal force, and the materials meet the current of air whirling upward through the separating chamber. The heavier particles or tailings gravitate downward through the upward air current into the cone 19 and out through the discharge spout 21. The lighter particles are carried upward by the air current, flow past the periphery of the baffle plate 113, through the outlet opening 15 and over into the receiving or settling chamber 51. The whirl of the air current in said chamber causes the lighter particles to move outward toward the inner surface of the outer casing, and they flow along the same downward into the cone 7 and are discharged through the fines outlet 25. Since the vanes 43 at the inlet opening contribute to the whirling motion of the air current, they tend to prevent return of the finer particles into the separating chamber.

The rotation of the distributor and baffle plates promotes whirl of the air in the separating chamber. Adjustment of the baffle plate relatively to the outlet opening will vary the volume of the air current through said opening. The baffle plate will have the greatest tendency to reduce the volume of the rising air current passing through the outlet opening when it is in its position of adjustment nearest the outlet opening as shown. The baffle plate in all of its adjustments is preferably well up in the drum 11 of the inner casing. Variation in the volume of the air current through the outlet opening may be further accomplished by varying the size of the valve opening by adjustment of its plates as described.

In my copending application Serial No. 113,395, filed June 3, 1926, is disclosed a separator similar in some respects to the separator of the present application, and included and claimed therein are a hopper provided with a flap valve and a fan having a hub in the separating chamber, arms projecting obliquely outward and upward from the

hub through an opening at the top of the separating chamber and carrying blades located above the separating chamber.

The upstanding flanges or vanes 117 of the baffle plate 115 are of substantial width and operate as a centrifugal agitator which strikes the particles and the impact of the vanes thereon disintegrates and breaks up larger particles which may be formed by smaller particles adhering together, thereby increasing the percentage of fines which may be carried over into the settling chamber. This centrifugal agitator also increases the whirl of the air current in the separating chamber closely adjacent to the top thereof and with transverse spiral action with respect to the air current whirling and rising in the separating chamber toward and past the centrifugal agitator. The centrifugal effect of the agitator throws the heavier particles out toward the wall 11 of the separating chamber so that they may gravitate down along said wall and be prevented from passing inward between the baffle plate and the top of the separating chamber and thence on to and through the outlet opening and into the settling chamber.

The fan draws the air current up through the separating chamber and blows the same down through the settling chamber. The vanes 43 at the inlet opening are arranged to promote the whirl of the air current passing from the settling chamber into the separating chamber and the centrifugal agitator intensifies the whirl of the air current at a place which is directly beneath and adjacent to the top of the separating chamber where it desirably increases the efficiency of separation.

40 The baffle plate being of ample area and extending well out toward the wall of the separating chamber and being located well up adjacent to the top of the separating chamber prevents the upward whirling air current, on passing the distributor plate, from flowing inward directly to the outlet opening, and causes the air current to be deflected outward toward the wall of the separating chamber in approaching the outlet opening. The centrifugal agitator also contributes to this effect.

By adjustment of the combined baffle plate and the rotary agitator relatively to the outlet opening, the volume of the air current passing through said opening may be varied. The nearer they are to the opening, the greater will be the reduction in the volume of air passing through the opening. The area of the flanges or vanes of the centrifugal agitator is relatively small as compared to the area of the blades of the fan so that the latter has the principal burden of causing the air current to circulate through the chambers.

65 Since the distributor and baffle plates are

formed of sections, they may be readily separated and others substituted therefor, suitable man holes (not shown) being provided to allow access to said plates.

It will be understood that the invention is not limited to the specific embodiment shown, and that various deviations may be made therefrom without departing from the spirit and scope of the appended claims.

What is claimed is:

1. A separator comprising in combination, an outer casing, an inner casing spaced from the outer casing and having an upper portion and a lower conical portion, a shutter between the upper and lower portions, the upper portion having an outlet opening at the top thereof, a fan in the outer casing above the outlet opening for causing air to circulate up in the inner casing, through the outlet, past the fan, down in the space between the casings and through the shutter into the inner casing, a vertical shaft extending down through the outlet opening into the inner casing, a rotary distributor carried by the shaft an upper baffle plate in the inner casing, means to adjust the baffle plate toward or from the outlet opening and cause it to cooperate with the outlet opening thereby to vary the volume of the air passing through said opening, means for delivering material to be graded to the rotary distributor, and a valve for the outlet opening having provision for varying the size of the outlet opening, thereby further to vary the volume of the air passing through the opening.

2. A separator comprising in combination, a separating chamber and a settling chamber having inlet and outlet openings between them, a fan above the outlet opening for causing air to circulate through said chambers and openings, a vertical shaft extending down through the outlet opening into the separating chamber, a rotary distributor on the shaft comprising a lower plate, and an upper plate in the separating chamber adjustable toward or from the outlet opening and cooperating with the outlet opening to vary the volume of the air passing therethrough, and feed means having a chute extending through the outlet opening for delivering materials to be graded to the distributor.

3. An air separator comprising in combination, a separating chamber and a settling chamber having inlet and outlet openings between them, a fan for causing air to circulate through said chambers and openings, a rotary distributor for delivering materials to be graded into the separating chamber comprising upper and lower plates in the separating chamber, and means to adjust the upper plate relatively to the outlet opening and cause it to cooperate with the outlet opening thereby to vary the volume

- of the air current passing through the outlet opening.
4. An air separator comprising in combination, a separating chamber and a settling chamber having inlet and outlet openings between them, a fan for causing air to circulate through said chambers and openings, a rotary distributor plate for delivering materials to be graded into the separating chamber, a baffle plate located beneath and adjacent the outlet opening, and means carried by the lower plate to adjust the baffle plate relatively to the outlet opening and cause it to cooperate with the latter thereby to vary the volume of the air current through the outlet opening. 70
5. An air separator comprising in combination, a separating chamber and a settling chamber having inlet and outlet openings between them, a fan for causing air to circulate through said chambers and openings, a rotary distributor for delivering materials to be graded into the separating chamber comprising upper and lower plates, and means including three screws for adjusting the upper plate relatively to the outlet opening, thereby to vary the volume of the air current through the outlet opening. 75
6. An air separator comprising in combination, a separating chamber and a settling chamber having inlet and outlet openings between them, a fan for causing air to circulate through said chambers and openings, a rotary distributor for delivering materials to be graded into the separating chamber comprising a lower plate, a shell rising from the lower plate, a ring encircling the shell, a baffle plate on the ring, and means to adjust the ring and baffle plate along the shell, thereby to vary the distance of said plate from the outlet opening. 80
7. An air separator comprising in combination, a separating chamber and a settling chamber having inlet and outlet openings between them, a fan for causing air to circulate through said chambers and openings, a rotary distributor for delivering materials to be graded into the separating chamber comprising a lower plate, a ring, an upper plate secured to the ring, recesses in the ring, nuts in the recesses, and screws rising from the lower plate and threaded to said nuts for adjusting the upper plate relatively to the lower plate. 85
8. An air separator comprising in combination, a separating chamber and a settling chamber having inlet and outlet openings between them, a fan for causing air to circulate through said chambers and openings, a rotary distributor for delivering materials to be graded into the separating chamber comprising a lower plate, a shell rising therefrom, a ring encircling the shell, an upper plate composed of sections secured to the ring, and screws rising from the 90
- lower shell for adjusting the ring and upper plate along the shell, thereby to vary the distance of the upper plate from the outlet opening.
9. A separator comprising in combination, a separating chamber and a settling chamber having inlet and outlet openings between them, a fan for causing air to circulate through said chambers and openings, a rotary distributor for delivering materials to be graded into the separating chamber and comprising a lower plate and a baffle plate, means to adjust the baffle plate toward or from the outlet opening, and a valve for the outlet opening having provision for varying the size of the outlet opening. 95
10. An air separator comprising in combination, a separating chamber and a settling chamber having inlet and outlet openings between them, a fan above the outlet opening for causing air to circulate through said chambers and openings, a rotary distributor plate in the separating chamber, a rotary baffle plate having stiffening flanges, and located adjacent to the outlet opening and means to adjust the baffle plate toward or away from the outlet opening, thereby to cause the baffle plate to cooperate with the outlet opening and vary the volume of the air current passing through the opening. 100
11. An air separator comprising in combination, a separating chamber and a settling chamber having inlet and outlet openings between them, means for causing air to circulate through said chambers and openings, a rotary distributor plate in the separating chamber, and a rotary baffle plate in the separating chamber between the distributor plate and the outlet opening and adjustable toward and from said opening, said baffle plate being adjacent to the outlet opening and having its periphery adjacent to the wall of the separating chamber, thereby forming a constricted passage for the air current passing the baffle plate to the outlet opening. 105
12. An air separator comprising in combination, a separating chamber and a settling chamber having inlet and outlet openings between them, means for causing air to circulate up through the separating chamber and down through the settling chamber, a shaft extending into the separating chamber, and a rotary baffle plate carried by said shaft having sections separable to facilitate their removal from the separator, and means for adjusting said plate toward and away from the outlet opening. 110
13. An air separator comprising in combination, a separating chamber and a settling chamber having inlet and outlet openings between them, a fan for causing air to circulate up through the separating chamber and down through the settling chamber, a shaft extending into the separating chamber, 115
- 65

5 a rotary distributor comprising a base secured to said shaft, a plate on said base, a shell mounted on the base, a fan above the outlet opening having a hub secured to the shell, a ring encircling the shell, a baffle plate mounted on the ring and located in the separating chamber beneath the outlet opening, and means for adjusting the ring and baffle plate toward or away from the 10 outlet opening.

14. An air separator comprising in combination, a separating chamber and a settling chamber having inlet and outlet openings between them, means for causing air to circulate through said chambers and openings, a shaft projecting through the outlet opening into the separating chamber, a rotary distributor on said shaft having holes therein, and mixing blades entered up through 20 said holes a substantial distance above the distributor and secured to the latter, said blades being removable down through said holes.

15. An air separator comprising in combination, a separating chamber and a settling chamber having inlet and outlet openings between them, means for causing air to circulate through said chambers and openings, a chute for conducting materials into the 25 separating chamber, a shaft projecting down through the chute, a rotary distributor on said shaft for receiving the materials from the chute, said distributor having holes therein, and mixing blades entered up 30 through said holes a substantial distance above the distributor plate, said blades being removable down through the holes in said plate.

16. An air separator for grading materials comprising, in combination, communicating separating and settling chambers, said separating chamber having a top with an outlet opening therein, means for causing an air current to circulate through said chambers, a rotary distributor in the separating chamber for receiving materials and delivering the same into the path of the air current rising in the separating chamber, and a rotary baffle plate in the separating chamber located adjacent to the outlet opening and extending well out toward the wall of the separating chamber for deflecting the air current and the materials carried up thereby outward beyond the edge of the plate in approaching the outlet opening, said rotary baffle plate having flanges for intensifying the whirl of the air current with spiral action directly beneath the top of the separating chamber, for breaking up particles and 50 driving heavier particles out toward the wall of the separating chamber and preventing them from being carried by the rising air current through the outlet opening over into the settling chamber.

17. An air separator for grading materials comprising, in combination, communicating separating and settling chambers having inlet and outlet openings between them, a fan for causing a whirling air current to circulate through said chambers and openings, 70 and a combined baffle plate and centrifugal agitator in the upper end of the separating chamber beneath and closely adjacent to the outlet opening for outwardly deflecting the air current approaching the outlet opening 75 and for intensifying the whirl of the air current in the separating chamber adjacent to the outlet opening.

18. An air separator for grading materials comprising, in combination, communicating separating and settling chambers, said separating chamber having an outlet opening in the top thereof, a fan having blades above said outlet opening for causing an air current to circulate through said chambers, and 85 a centrifugal agitator having vanes in the separating chamber beneath and adjacent to the outlet opening for intensifying the whirl of the air current with transverse spiral action relatively to the air current produced 90 by the fan, the vanes being relatively small as compared to the blades.

19. An air separator for grading materials comprising, in combination, communicating separating and settling chambers, said separating chamber having a top with an outlet opening therein, a fan having blades above the outlet opening for causing an air current to circulate through said chambers, a baffle plate in the separating chamber beneath 100 and adjacent to the outlet opening, and a centrifugal agitator between the baffle plate and the outlet opening for intensifying the whirl of the air current directly beneath the top of the separating chamber.

20. An air separator for grading materials comprising, in combination, communicating separating and settling chambers, said separating chamber having an outlet opening in the top thereof, a fan for causing an air current to circulate through said chambers with a rising movement in the separating chamber, means to distribute materials to be graded in the path of the rising air current, a baffle plate in the separating chamber adjacent to the outlet opening, and a rotary centrifugal agitator between the baffle plate and the outlet opening.

21. An air separator for grading materials comprising, in combination, communicating separating and settling chambers, said separating chamber having a top with an outlet opening therein, a fan having blades above the outlet opening for causing an air current to circulate through said chambers, a baffle plate in the separating chamber beneath and adjacent to the outlet opening, and means between the baffle plate and open-

ing for intensifying the whirl of the air current passing the baffle plate and approaching the outlet opening.

22. An air separator for grading materials comprising, in combination, communicating separating and settling chambers, said separating chamber having a top with an outlet opening therein, a fan having blades above the outlet opening for causing an air current 10 to circulate through said chambers, a baffle plate in the separating chamber adjacent to the outlet opening, a centrifugal agitator between the baffle plate and the outlet opening, and means for adjusting the baffle plate 15 and centrifugal agitator toward or from the outlet opening.

23. An air separator for grading materials comprising, in combination, communicating separating and settling chambers, said separating chamber having inlet and outlet openings, a fan for causing a whirling air current to circulate through said chambers and openings, vanes at the inlet opening for promoting whirl of the air current passing through the inlet opening, a baffle plate in 25 the separating chamber beneath and adjacent to the outlet opening, and a centrifugal agitator between the baffle plate and the outlet opening for intensifying the whirl of the air current between the baffle plate and 30 the outlet opening.

THOMAS J. STURTEVANT.
